DESIGN FOR A FOLDING TIE RACK

Joseph Cooper, New York, N. Y.

Application August 7, 1945, Serial No. 121,307

Term of patent 3½ years

(Cl. D33—8)

To all whom it may concern:

Be it known that I, Joseph Cooper, a citizen of United States, residing at New York, in the county of New York and State of New York, have invented a new, original, and ornamental Design for Folding Tie Racks, of which the following is a specification, reference being had to the accompanying drawing, forming part thereof.

In the drawing—

Fig. 1 is a top plan view of a folding tie rack showing my new design.

Fig. 2 is a perspective view thereof, and Fig. 3 is a perspective view of the folding tie rack shown in Fig. 1 as it appears in folded position.

I claim:

The ornamental design for a folding tie rack, as shown.

JOSEPH COOPER.
